The ornamental design for a soap stand for a kitchen airgap, as shown and described.

DESCRIPTION

FIG. 1 is a perspective view of a soap stand for a kitchen airgap, showing my new design;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof;

FIG. 8 is a cross-sectional view taken along the line **8-8** of FIG. 3; and,

FIG. 9 is another front view thereof, in which a liquid dispenser is shown mounted over the soap stand for a kitchen airgap in order to illustrate a sample environment. The broken lines in the figures show portions of the soap stand for a kitchen airgap which form no part of the claimed design.

The broken lines in FIG. 9 depict an environmental liquid dispenser that forms no part of the claimed design.
